(57) **CLAIM**

The ornamental design for a combined bottle and cap, as shown and described.

DESCRIPTION

FIG. 1 is a top perspective view of a first embodiment of a combined bottle and cap showing my new design;

FIG. 2 is a second top perspective view thereof;

FIG. 3 is a front view thereof;

FIG. 4 is a right side view thereof;

FIG. 5 is a rear view thereof;

FIG. 6 is a left side view thereof;

FIG. 7 is a top view thereof;

FIG. 8 is a bottom view thereof;

FIG. 9 is a top perspective view of a second embodiment of my new design for the combined bottle and cap;

FIG. 10 is a second top perspective view thereof;

FIG. 11 is a front view thereof;

FIG. 12 is a right side view thereof;

FIG. 13 is a rear view thereof;

FIG. 14 is a left side view thereof;

FIG. 15 is a top view thereof; and,

FIG. 16 is a bottom view thereof.

The dashed lines in depict portions of the combined bottle and cap that form no part of the claim to the embodiment in which they are shown.

1 Claim, 9 Drawing Sheets
